UNITED STATES PATENT OFFICE.

LEWIS ARTHUR CLAPP, OF CHICAGO, ILLINOIS.

RAIL-JOINT.

1,183,798.

Specification of Letters Patent.

Patented May 16, 1916.

Application filed January 28, 1916. Serial No. 74,756.

To all whom it may concern:

Be it known that I, LEWIS ARTHUR CLAPP, a citizen of the United States, residing at Chicago, in the county of Cook and State 5 of Illinois, have invented a certain new and useful Improvement in Rail-Joints, of which the following is a specification.

This invention is a new and improved rail joint, intended to make a railroad track 10 which is substantially as smooth for the passage of trains over the joints in the rails as in other parts of the rails, both when the track is first laid and at substantially all times later in its life.

As it is for many reasons absolutely necessary to make railroad track of a plurality of rails of convenient length both for manufacture and transportation, it is necessary to have between adjacent rails placed end 15 to end a slight space, and to bridge that space with a splicing device. In the past, these splicing devices have been of such a character that when the track has been in use a little time the passing wheels pound 20 down and flatten these rail ends, the trouble increasing with the age of the track. It has heretofore been generally supposed that this flattening of the rail ends is due simply to the lack of continuous support for 25 the circumferences of the car wheels as they pass over the slight spaces between the rail ends, but I have found that this is not the true cause of the flattening of the rail ends.

When a rug or carpet is laid upon a floor 30 and a heavy object is passed over it, this passing object tends to bunch up the portions of the rug or carpet in front of it in a sort of a wave not unlike a water wave which is, of course, finally flattened out as the object reaches the edge of the carpet. Exactly 35 the same sort of thing tends to take place as the heavy wheels of a locomotive pass along a railroad rail. If the rail is of uniform strength throughout its length, this wave motion or tendency to wave motion in the rail is uniform and the rail offers a uniform 40 support to the passing wheel throughout its length without jump or jar by the passing wheels. If, however, the rails of the track 45 are not of substantially uniform structure and weight sustaining strength, this wave motion along the rail is interfered with and the passing wheels cease to be so uniformly supported, as described, and therefore, 50 settle downward too much if the strength of

the support is weakened and, on the other hand, jump if the strength of the support is suddenly increased. What has happened in structures of the past has been that a solid rigid clamping device was applied to the 55 ends of the rail extending back from twelve to eighteen inches from the joint over the joint ties, thereby greatly strengthening and stiffening the twelve or eighteen inches of rail immediately adjacent to the joint, or if 60 they did not extend over the joint ties they were of uniform rigidity throughout, the result being that when a heavy wheel traveling from the middle of the rail toward the end and creating the wave movement above 65 described in the rail toward its end, abruptly reaches the inner end of this heavy reinforcement, the uniformly yielding support of the normal rail and the wave motion resulting therefrom was rudely broken, and 70 the support being stronger than the normal rail, the wheel was thrown upward or jumped, landing, in the forward movement of the train, again on the rail at a point very close to the actual juncture of the two 75 adjacent rail ends, the pound thus created flattening the rail ends in the manner described, not as has heretofore been supposed due to the fact that there is a slight space between the rail ends, but to this jumping of the wheel due to the sudden variation 80 in the supporting power of the rail immediately adjacent to the end.

The object of this invention is to provide 85 a device constructed in accordance with this new theory which does away with the jumping of the wheels of the passing train as they approach the rail joints, thus saving the flattening of the rail ends adjacent to the joint and doing away with the tremendous expense occasioned by the necessity of frequent rail renewals and frequent ballasting to overcome the settling of the track at 90 the rail joints and so forth.

The invention consists in a device capable 95 of holding the actual ends of the adjacent rails in fixed proper horizontal and vertical relationship to each other without impairing the normal elasticity of the rail. This permits the normal wave motion of the rail under the action of a given wheel passing over, to travel throughout the entire length of the rail and thus prevents all jumping of the rail, as heretofore described.

The invention further consists in the fea- 100

tures and details of construction which will be hereafter more fully described in the specification and claims.

Referring to the drawings, in which similar numerals indicate the same parts throughout the several views, Figure 1 is a side view of two rail ends joined together by a device illustrating this invention in its preferred form. Fig. 2 is a sectional view taken on the line 2—2 of Fig. 1. Fig. 3 is a sectional view taken on the line 3—3 of Fig. 1. Fig. 4 is a sectional detail view on the line 4—4 of Fig. 1, with a slight illustrative modification to be hereafter described. Fig. 5 is a perspective view of one of the splicing members removed from the rail ends. Fig. 6 is a sectional view of a portion of the rail and portions of the splicing members removed from the lower central portion of Fig. 4 and enlarged.

Fig. 1 shows two adjacent rail ends 10 and 12 to be spliced, the same being supported on two ties 14 and 16, preferably placed the standard distance of about twelve and one-half inches apart. The splice members proper, one for each side of the joint, consist, broadly speaking, of a central member 18, rigidly connected to a horizontally extending plate 20 provided with suitable holes 22 and 24 through which the usual bolts 26 and 28 respectively pass to secure the device to the rail ends. Each member 18 is preferably made of considerably less length than the distance between the ties 14 and 16; in practice, about six inches, or three inches each side of the space 30. It will be noticed by an inspection of Fig. 3 that the portions of member 20 which are beyond the ends of member 18, lettered for convenience 20^a, have no bearing on the flange of the rail, though they do bear upon the under sides of the head of the rail, thus giving the head of the rail what support the bolts 26 or 28, as the case may be, can afford. This stiffens the rail end somewhat, but not as much as the central splice to be hereafter described and this affords a graduation in supporting power from the normal rail to the central splice. On the other hand, the central portion of the member 20, lettered for convenience 20^b, not only bears against the under side of the head of the rail in the line 32 (Fig. 4), but is also brought down to bear against the upper side 55 of the adjacent rail flange in the line 34 (Fig. 4). These two lines or surfaces 32 and 34 are angularly inclined toward the web of the rail and as the member 20^b is forced in the same direction through the action of the bolts 24 and 26, we have this member 20^b rigidly engaging the rail throughout its six inches of length, which length extends over the space 30 between the rail ends, as heretofore described; thus, for this six inches, 60 more or less, securing the ends of the rail

ends in fixed relation to each other with the upper edges of the rail ends level, as shown in Fig. 1, and the side edges of the rail heads in direct alinement one with the other. Thus, the outer end portions 20^a of member 20 reinforce or stiffen the rail to a substantially less degree as heretofore described, whereby the wave motion created by a wheel passing over the rail travels right up to the rail end without any sudden change.

The device thus far described would be very efficient in practice and very valuable, but due to the wave motion heretofore described, there might be a tendency to wear along the surfaces 32, heretofore described, and in order to combat this it is preferable to apply to the base of each central portion of each splice member, heretofore described, the member 18, clearly shown in the drawings, extending around the extreme outer edge 36 of the adjacent rail flange and made, as clearly shown in Fig. 4, with a wedge shaped opening 38 which, when the device is driven in place, rigidly clamps the outer edge 36 only of the rail flange. This gripping of the edge 36 of the rail flange prevents rotation of the member 20^b about a center at 38', (Fig. 4) and thus prevents lateral movement of the adjacent parts along the surfaces of contact 32, heretofore described, and does away with wear at that point, thus insuring each member 20^b in its work of reinforcing the rail ends for the three inches, more or less, on each side of the space 30, in the manner heretofore described.

In the operation of the device, the parts are applied and assembled in the position shown in the drawings, and made clear by the preceding description. When a wheel of a loaded car passes along either rail 10 or rail 12 from outside the view of Fig. 1, it finds the rail on which it is traveling of substantially uniform strength and elasticity until it reaches the outer end of members 20. Here for the length of end portion 20^a the rail is stiffened but not sufficient to cause the wheel to jump and it, therefore, becomes accustomed to this change in the supporting strength of the rail without jump and it is, therefore, prepared to reach and travel over the central portion of the device which, as described, is still stiffer than the end portions without jump. The same changes occur in reversed order as the wheel moves from the center of the splicing device onto the next rail.

Having thus described my invention, what I claim as new and desire to secure by Letters Patent, is:

1. In a device of the class described, the combination of two rail ends to be joined, a splice member extending along said rails for a distance on opposite sides of the point of juncture of the rails, said splice member in

its central portion engaging the under side of the head of the rail and the top of the flange of the rail and in its end portion engaging only the under side of the head of the rail.

2. A device of the class described, the combination of two rail ends to be joined, a splice member extending along said rails for a distance on opposite sides of the point of juncture of the rails, means securing the splice member to the end portion of each rail, said splice member in its central portion bearing against the under side of the head of the rail and the top of the flange of the rail and in its end portion engaging only the under side of the head of the rail.

3. In a device of the class described, the combination of two rail ends to be joined, a splice member extending along said rail ends for a distance on opposite sides of their point of juncture, said splice member throughout substantially its entire length engaging the under sides of the heads of the adjacent rail ends while it only bears upon the tops of the flanges of the adjacent rail ends for a shorter distance on each side of their point of juncture.

4. In a device of the class described, the combination of two rail ends to be joined, a splice member extending along said rail ends for a distance on opposite sides of their point of juncture, means securing the splice member to the end portion of each rail, said splice member throughout substantially its entire length engaging the under sides of the heads of the adjacent rail ends while it only bears upon the tops of the flanges of adjacent rail ends for a shorter distance on each side of their point of juncture.

40 5. In a device of the class described, the combination of two rail ends to be joined, a splice member extending along the rails for a distance on opposite sides of the point of juncture of said rail ends, said splice member in its central portion engaging the under sides of the heads of the rails and the tops of the flanges of the rail and in its end portions engaging only the heads of the rails, the splice device being normally located over

50 the space between two adjacent ties on which the rail ends are supported, and the central portion of the splice member being of less length than the distance between the ties.

6. In a device of the class described, a

rail splice member consisting of a substantially straight bar adapted to lie under the head of a rail and throughout substantially the length of the bar to bear against the rail head, means for securing said bar to the rail, there being at the central portion of this bar a member which of substantially less length than the bar, takes bearing upon the surface of the flange of the rail and is locked against rotation toward or from the rail by engaging the outer edge of the rail flange.

7. In a device of the class described, in combination with two rail ends abutting each other, a splice member placed over the point of juncture of the rail ends having a vertical member bearing at its top against the under edges of the heads of the adjacent rail ends and clearing the webs of the rails down to a point adjacent to the flanges of the rails where it takes bearing on the webs of the rails, thereby allowing rotation of said vertical member toward the rail webs as wear takes place between the top of said member and the rail heads and having a generally horizontal member extending therefrom which passes over and bears against the outer edges of the flanges of the rails, this in combination with adjustable devices designed to secure said vertical portion of the splice member to the rails whereby tightening said securing devices tends to force the respective parts enumerated to grip the under edges of the heads of the rails and the edges of the rail flanges for the purposes set forth.

8. In a device of the class described, in combination with two rail ends abutting each other, an angular splice member adjustably secured to said rails, applied over the sides of adjacent ends of the rails, bearing against the under sides of the heads of the rails and the outer edges of the flanges of the rails and pivoted against intermediate portions of the rails to allow rotation toward the rail webs as wear takes place at the contacts with the rail heads and flanges.

In witness whereof, I have hereunto subscribed my name in the presence of two witnesses.

LEWIS ARTHUR CLAPP.
